UNITED STATES PATENT OFFICE.

JAMES PAGES, OF BROOKLYN, NEW YORK.

PLASTERING MACHINE.

Application filed June 2, 1928. Serial No. 282,339.

My present invention relates to a new and useful device in the nature of a plastering machine adapted for applying plaster to walls and ceilings.

5 The object of the invention is to provide a plastering machine of comparatively simple construction, positive in action and easily operated and manipulated.

Fig. 1 is a front elevational view of my improved plastering machine showing the scaffold attached thereto.

Fig. 2 is a side elevational view thereof.

Fig. 3 is a horizontal sectional view taken on the line 3—3 of Fig. 1.

15 Fig. 4 is a similar sectional view taken on the line 4—4 of Fig. 1.

Fig. 5 is an enlarged vertical sectional view of the ceiling box as embodied in my improved machine.

20 Fig. 6 is a similar sectional view of the wall box as embodied in my improved machine.

As here embodied my improved plastering machine comprises a frame work consisting

25 of upright members 10, 11, 12 and 13, and suitable lower and upper cross supports 14, 15, 16, 17 and 18, 19, 20, 21, secured thereto, so as to provide a suitable structure or supporting means.

30 Shafts 22 and 23 are rotatively mounted in the lower extremities of the upright members and have secured thereto respectively, wheels 24, 25 and 26, 27, which permits my improved machine to be readily pushed or pulled in one direction as hereinafter set forth.

Shafts 28 and 29 are secured to a platform 30 and have rotatively mounted thereon wheels 31, 32 and 33, 34 respectively. A

40 screw member 35 is threadedly mounted in a cross support 36, secured to the above mentioned cross support 17 and to motor housing 37. The screw member 35 is provided with an enlarged lower extremity 38, rotatively positioned in a suitable recess formed in the block member 39 secured to the platform 30. The screw member 35 has secured thereto at its upper extended extremity a lever 40 or handle member, for the purpose of

45 manually rotating the said screw member. A guide 41 shown in Fig. 3 is secured to the motor housing 37, and is extended downwardly therefrom freely engaging in an opening formed in the platform 30.

55 The above described construction is such

as will permit the wheels 31, 32, 33 and 34, to be lowered somewhat below the first mentioned wheels 24, 25, 26 and 27, as designated by the reference numeral 42 in Fig. 2, when the lever 40 is rotated, which permits my improved device to be readily pushed or pulled in a direction at right angles to the direction provided by the first mentioned wheels. It is obvious that the guide 41 will prevent the rotation of the platform 30, and thereby maintain the desired relative position of the wheels secured to the platform 30.

An electric motor 42 is mounted in the motor housing 37 and is operatively connected by means of suitable electric wires 43 and 44 to a switch 45, of the conventional type, mounted on the upright member 11. The switch 45 is operatively connected by means of electric wires 46 and 47, to any convenient suitable source of electric current, not shown in the accompanying drawing. The latter described construction is such as will permit the said electric motor to operate or rotate the mechanism as hereinafter set forth.

55 A sprocket wheel 48 is mounted on the armature shaft of the motor 42. A flexible chain 49 is extended over the sprocket wheel 48 and over a sprocket wheel 50 mounted on the shaft 51, rotatively mounted in brackets 52 and 53 secured to the motor housing 37.

A worm 55 is mounted on the shaft 51 and meshes with a worm wheel 56 secured to the shaft 57 rotatively mounted in a bracket 58 secured to the motor housing 37 and in the bracket 59 secured to the cross member 15.

60 A flexible chain 61 is extended over the sprocket wheel 60 mounted on the shaft 57 and over a sprocket wheel 62 secured to the stub shaft 63 rotatively mounted in the bracket 64 secured to the cross support 15, and rotatively engaged in the tubular member 65 secured as at 66 to the shaft 67 rotatively mounted in the bracket 68 secured to the cross support 16. The shaft 67 has secured thereto at its extended extremity a hand wheel 69.

65 The shaft 67 has formed therein at its extremity a notch 70 adapted to slidably engage over the extended element 71 of the stub shaft 63. A sprocket wheel 72 is secured to the above mentioned sprocket wheel 62. A flexible chain 73 is extended over the sprocket wheel 72 and over a sprocket wheel 74 rotatively mounted on the shaft 75.

70 The dog 77 is slidably mounted on the shaft 75 and has formed therein an opening adapt- 100

75

ed to receive the key 78 secured to the shaft 75. A lever 78^a is pivotally mounted on the bracket 79 secured to the upright member 10 and is provided with a fork shape extremity 80 adapted to freely engage in a co-axial groove formed in the dog 77. The shaft 75 is rotatively mounted in the brackets 81 and 82 secured respectively to the cross supports 15 and 16. A drum 76 is secured to the 10 shaft 75.

The above described construction is such as will permit the drum 76 to be rotated by the electric motor 42 when the dog 77 is slidably engaged with the radial teeth 83 formed 15 in the sprocket wheel 74. The said construction is also such as will permit the shaft 67 to be rotated by the electric motor 42 when the notch 70 of the shaft 67 is engaged with the extended element 71 of the stub shaft 63. 20 It is obvious that the said shaft 67 may be manually rotated by the rotation of the hand wheel 69.

A flexible chain 85 shown in Fig. 2 is extended over the sprocket wheel 84 secured to 25 the shaft 67 and over a sprocket wheel 86 secured to the shaft 87 rotatively mounted in brackets 88 and 89 secured to the cross supports 15 and 16. A flexible chain 91 is extended over the sprocket wheel 90 secured to 30 the shaft 87 and over a sprocket wheel 92 secured to the above mentioned shaft 23. The above described construction is such as will permit the rollers 26 and 27 to be rotated by the hand wheel 69, or by the electric motor 35 42, as a means of readily transporting or rolling my improved machine on the rollers 24, 25, 26 and 27, to any desired place.

A lever 93 shown in Figs. 1 and 2 is pivotally secured intermediately, as at 94, to the 40 extended free extremity of the link 95, pivotally mounted on the shaft 96 secured to the upright members 10 and 11. A tension spring 97 is secured to the free extremity of the link 95 and to the motor casing 37, as a means of 45 normally holding the pointed lower extremity 99 of the lever 93 in disengagement with the floor. The above described construction is such as will permit the pointed extremity 99 of the lever 93 to be engaged with the said 50 floor when the lever is pressed or forced downwardly by the foot of the operator of my improved machine as a means of holding my improved machine in any desired position on the floor.

Upright members 100 and 101 are supported by cross members 102 and 103, and have secured thereto, and extended therefrom angle members, 104, 105 and 106, 107 respectively, vertically disposed and adapted to slidably 60 engage the upright members 108 and 109, respectively which are provided with extended elements adapted to receive the said angle members.

A box like member 110, open at the top 65 and bottom, has secured thereto at its lower

portion brackets 111 and 112, adapted to receive the pins 113 and 114, secured to the upper extremities of the upright members 105 and 106, respectively as a means of pivotally mounting the said box like member on the 70 said upright members. Tension springs 114 and 115 are secured to the opposite sides of the box like member 110 and to the upright members 105 and 106, as a means of normally holding the said box like member in an approximately horizontal position. 75

An operating lever 116 is pivotally mounted intermediately, on the pin 118 carried in the brackets 119 mounted on the cross member 102. A movable member 121 is hinged as 80 at 122, by a pin or the like to the lug element 123 of the box like member 110, at the upper edge thereof, and is of suitable size to enclose the open lower end of the said box like member. The movable member 121 is angularly 85 downwardly disposed and has its free extended edge resting upon the roller 124 rotatively mounted on the pin 125 secured to the free extremity of the operating lever 116. The box like member 110 has the inner side 90 formed or shaped arc like, as at 126, so as to permit of free movement of the movable member 121 in the said box like member.

A flexible member 127, a cord, cable or the like is secured as at 128, at one extremity to 95 the cross member 18 and is extended downwardly therefrom over a pulley 129, secured in proximity to the cross member 103, and is extended upwardly therefrom as at 130, over the pulley 131 secured to the cross member 18. 100 The flexible member 127 is extended downwardly therefrom, as at 131 and is extended or wound one turn on the drum 76, and is extended therefrom as at 132 and is secured as at 133 to the upright member 11. 105

The latter described construction is such as will permit the said box like member 110 to be vertically raised when the flexible member 127 is pulled tight on the drum 76, by the operator of my improved machine, who pulls in 110 the said flexible member in proximity to the extremity 133 of the flexible member.

A flexible member 134, is secured as at 135 intermediately to the cross member 136 secured to the upright members 100 and 101 115 and is extended upwardly therefrom over the pulley 137 secured to the extremity of the lever 116, opposite the pulley 124 and is extended downwardly therefrom as at 138 over the pulley 139 secured to the cross member 136, and is extended upwardly therefrom as at 140 over the pulley 141 secured to the extremity of the lever 116, adjacent to the pulley 137 and is extended downwardly therefrom as at 142 and is secured to the shaft 67. 120

The above described construction is such as will permit the plaster mixture 143 placed in the box like member 110, on the movable member 121 to be forced outwardly therefrom by the said movable member, which is 125 130

hinged upwardly by the lever 116 when the said shaft 67 is rotated manually by the hand wheel 67 or by the electric motor 42.

It is understood that the box like member 5 is raised vertically so as to permit its extended lip 110 to engage or strike the laths 143 secured to the ceiling of the room to be plastered and that my improved machine is rolled along the floor, as above set forth, during the operation 10 of the operating lever, as a means of spreading the plaster mixture contained in the said box like member.

A box like member 144 is slidably mounted vertically on the upright members 13 and 14, 15 and has hinged thereto as at 145, a container 146, of scooplike construction, provided with a lower extended edge 147 and sides 148, which also extend from the main portion thereof. A lever 149 is pivoted as at 150 to the box like member 144 and is extended therefrom and engages the container 146, at its free extremity. A lever 151 is secured to the pivot point of the first mentioned lever 149 and is provided with a handle element 152. 20 The latter described construction is such as will permit the container 146 to be hinged outwardly by the manual movement of the handle element 152. A limiting member 153 or stop is secured to the container 146 as a means of 25 limiting the movement of the lever 149.

A flexible member 154 is secured to the box like member 144 and is extended upwardly therefrom over a pulley 155 secured to the upper portion of the cross member 21. The 30 flexible member 154 is extended downwardly from the pulley 155 as at 156 over the pulley 157, secured to the box like member 144 and is extended upwardly therefrom as at 158, over the pulley 159 secured to the cross member 21, and is further extended downwardly therefrom as at 160, over the pulley 161 secured to the box like member 144. The flexible member 154 is extended upwardly from the pulley 161, as at 162 over the pulley 163 35 secured to the cross member 21 and is further extended therefrom as at 164, and is wound or extended around the above mentioned drum 76, as at 165 and is secured as at 166 to the upright member 11.

40 The above described construction is such as will permit the box like member 144 and the container 146 to be raised vertically when the flexible member 154 is manually pulled tight on the drum 76, by the operator of my improved machine who grips the flexible member 154 in proximity to its extremity 166. The said construction is also such as will permit the plaster mixture 167 placed on the container 146 to be spread on the wall of the 45 room, when the said container is raised vertically by means of pressing or pulling the handle element 152 by the operating lever 151 downwardly.

In Fig. 1, of the accompanying drawing, 50 I have shown a scaffold embodying a frame

like member 168 of rectangular construction, horizontally disposed or mounted on suitable castors 169. A pair of end supports 170 and 171, of a frame like construction are hinged as at 172 and 173, respectively to the opposite extremities or ends of the frame 168, and are held in vertically extended positions therefrom, by means of angular supports 174 and 175, respectively, which are hinged as at 176 and 177 to the end supports 170 and 171 and 55 extend therefrom and engage in notches formed in the brackets 178 and 179 secured to the frame 168.

Rectangular members 184 and 185 or boards are adapted to extend intermediate the end supports 170 and 171 and are placed on any desired one of the cross members 186 and 187, as may be desired. Rectangular members 188 and 189 are hinged as at 190 and 191, respectively to the upper extremities of the end supports 170 and 171, and are held in a horizontal extended position therefrom by means of the supports 192 and 193, hinged as at 194 and 195, respectively to the rectangular members 188 and 189, and removably engage the extended elements 196 and 197 of the end supports 170 and 171.

The above described construction is such as will permit plaster mixture 198 and 199 to be placed on the rectangular members 188 and 189, and which will also permit workmen to stand on the boards 184 and 185 for the purpose of plastering the ceiling or walls of the room with the said plaster mixture as may be required to supplement the plastering placed on the said ceiling and walls by my improved machine.

55 A pair of engaging members 200 are secured as at 201 to the end support 171 and are provided with downwardly extended elements 202 or extremities, preferably of tapered construction adapted to engage in similar shaped openings 203 formed in the extended elements of the supports 204 secured as at 205 to the upright member 10. The above described construction is such as will permit the scaffold to be removably attached to my improved plastering machine for the purpose of permitting the scaffold to be moved along the floor with the plastering machine rendering same to be accessible at all times thus expediting the use of the said scaffold.

Having thus described my invention, what I claim as new and desire to protect by United States Letters Patent is:

60 1. In a plastering machine of the class described, a means for vertically raising a box like member when a flexible member secured thereto and extended over a drum is manually pulled tight, said drum operatively connected to an electric motor mounted on the platform of the said plastering machine, a means for forcing a plaster mixture placed on a movable member pivotally attached to the said box like member against the ceiling of a. 120

- room as a means of plastering the said ceiling when said plastering machine is rolled along the floor of the said room, a second box like member slidably mounted on upright members of the said plastering machine, a means for vertically raising the said second box like member when a flexible member secured thereto and extended therefrom over pulleys mounted on the frame of the said machine, and over the said drum is pulled tight, a container pivotally mounted on the said second box like member and extended therefrom, said container held in any desired extended position from the said second box like member by means of an operating lever, pivotally mounted on the said second box like member and connected to a lever adapted to engage the said container, as a means of plastering the wall of a room.
- 20 2. In combination with a plastering machine of the class described, a means for vertically raising a box like member when a flexible member secured thereto and extended over a drum is manually pulled tight, said drum operatively connected to an electric motor mounted on the platform of the said plastering machine, a means for forcing a plaster mixture placed on a movable member pivotally attached to the said box like member against the ceiling of a room as a means of plastering the said ceiling when said plastering machine is rolled along the floor of the said room, a second box like member slidably mounted on upright members of the said plas-

tering machine, a means of vertically raising the said second box like member when a flexible member secured thereto and extended therefrom over pulleys mounted on the frame of the said machine, and over the said drum is pulled tight, a container pivotally mounted on the said second box like member and extended therefrom, said container held in any desired extended position from the said second box like member by means of an operating lever, pivotally mounted on the said second box like member, and connected to a lever adapted to engage the said container, as a means of plastering the wall of a room.

3. In a plastering machine of the class described, a box like member slidably mounted on upright members of the said plastering machine, a means for vertically raising the said box like member when a flexible member secured thereto and extended therefrom over pulleys mounted on the frame of the said machine, and over a drum is pulled tight, a container pivotally mounted on the said box like member and extended therefrom, said container held in any desired extended position from the said box like member by means of an operating lever, pivotally mounted on the said box like member and connected to a lever adapted to engage the said container, as a means of plastering the wall of a room.

In testimony whereof I have affixed my signature.

JAMES PAGES.
